UNITED STATES PATENT OFFICE.

JAMES R. MOFFATT AND RALPH S. KELSO, OF CHICAGO, ILLINOIS, ASSIGNEES TO UNION SPECIAL MACHINE COMPANY, OF CHICAGO, ILLINOIS, A CORPORATION OF ILLINOIS.

LOOPER-OPERATING MECHANISM FOR SEWING-MACHINES.

1,283,862.

Specification of Letters Patent.

Patented Nov. 5, 1918.

Application filed December 21, 1916. Serial No. 133,222.

To all whom it may concern:

Be it known that we, JAMES R. MOFFATT and RALPH S. KELSO, citizens of the United States, residing respectively at Chicago, in the county of Cook, State of Illinois, have invented certain new and useful Improvements in Looper-Operating Mechanism for Sewing-Machines, of which the following is a description, reference being had to the accompanying drawing and to the figures of reference marked thereon.

The invention relates to new and useful improvements in looper operating mechanisms for sewing machines, and more particularly to a looper operating mechanism for a threaded looper which is disposed so as to move back and forth in substantially the line of feed for its loop-taking and loop-shedding movements.

An object of the invention is to provide a looper operating mechanism wherein the looper is moved positively back and forth, that is, into and out of the needle loop, and also positively laterally for its needle avoiding movement through devices connected with the main shaft below the work support, which devices are of comparatively few parts and free from springs and irregularly shaped cams.

A further object of the invention is to provide a machine of the above character wherein a plurality of loopers may be used, which loopers are arranged side by side and are movable in a direction parallel with the line of feed for their loop-entering and loop-leaving movements.

These and other objects will in part be obvious and will in part be hereinafter more fully disclosed.

In the drawings, which show by way of illustration one embodiment of the invention:

Figure 1 is a front view of a sewing machine embodying the improvements;

Fig. 2 is a longitudinal sectional view through a portion of the machine, said view being taken substantially on the line of the needles;

Fig. 3 is a plan view of the parts beneath the work support;

Fig. 4 is a view, partly in transverse vertical section and partly in elevation, substantially through one of the needles;

Fig. 5 is a transverse sectional view on the line 5—5 of Fig. 2;

55

Fig. 6 is a horizontal sectional view on the line 6—6 of Fig. 2.

We have shown our invention as applied to a sewing machine which is formed with a supporting bed 1 on which is mounted a work support 2. An overhanging arm 3 is carried by said supporting bed and a needle bar 4 reciprocates in the forward end of said overhanging arm. Said needle bar is reciprocated by a needle lever 5 which is connected to the needle bar by a link 6. The needle lever is oscillated by an eccentric strap 7 which co-operates with an eccentric on the main shaft 8. As herein shown, the needle bar is provided with a needle supporting head 9 which carries four needles, indicated at 10, 11, 12 and 13. The threads for the needles are led through suitable tensions, indicated at T, and thence through suitable thread guides carried in part by the needle lever and in part by the overhanging arm. The needle threads are indicated at t in the drawings.

The material is held on the work support by a presser foot 14. This presser foot is carried by a presser bar 15 which is mounted in the overhanging arm. Co-operating with the presser foot is a feed dog 16. This feed dog is carried by a feed bar 17, which is raised and lowered by a suitable cam on the main shaft, and which feed bar is moved back and forth through a connection with a feed rocker 18, which feed rocker in turn is operated by an eccentric strap 19 co-operating with an eccentric on the main shaft. It will be understood that there is a series of feed dogs which are adjustably connected with the feed bar 17 which carries a cross head 20 on which the feed dogs are mounted.

Co-operating with the needles 10, 11, 12 and 13, respectively, are four loopers 21, 22, 23 and 24. Each of these loopers is a thread-carrying looper, that is, it is provided with a thread eye through which the looper thread passes, that is to be concatenated with the needle thread loops. Each looper is carried by an independent looper holder, and these looper holders are each indicated at 25 in the drawings. These looper

holders are mounted on a looper carrier 26 which is formed of two sleeves 27 and 28 and a connected slotted cross bar 29. Each looper holder has a rearwardly extending shank which extends into the slot in the slotted cross bar (see Fig. 4), and a cap plate 30 secured to the looper holder 25 by a screw 31 clamps the looper holder on this cross bar 29. This provides a supporting means for the 10 loopers which permits said loopers to be independently adjustable and set so as to correspond to the arrangement of the needles on the needle bar. The loopers, as clearly shown in the drawings, are each mounted so that it 15 extends in a line parallel with the line of feed.

The looper carrier 26 has also a second cross bar 32 connected to the sleeves 27 and 28, and a small finger piece 33 is secured to the sleeve 28. The sleeves 27 and 28 are mounted so as to slide freely on the looper supporting shaft 34. A collar 35 is rigidly secured to the looper supporting shaft 34, and this collar is formed with spaced arms 25 36 and 37 (see Fig. 4) through which the cross bar 32 extends. This serves as a means for connecting the looper carrier to the looper supporting shaft so that, while it may be moved endwise on the shaft, it can 30 not be oscillated relative to the shaft.

The looper supporting shaft 34 is mounted in suitable bearings 38 and 39 carried by the supporting bed 1. The shaft extends beyond these bearings and is mounted to 35 turn freely in the bearings so that it may oscillate therein and also move endwise in the bearings. Said looper supporting shaft is oscillated by a link 40 which is connected to a crank arm 41 on the looper supporting shaft and also to a crank arm 42 on the main shaft 8. As the main shaft rotates, the 40 crank arm 41 will rotate, but the crank arm 41 is longer than the crank arm 42 and, therefore, the looper supporting shaft will 45 be oscillated.

The looper supporting shaft is moved endwise through devices connected to the other end of said looper supporting shaft. On the end of the shaft there is a sleeve 43 50 which is clamped thereto by the screw 44. This sleeve 43 projects beyond the end of the looper supporting shaft and a rod 45 extends into the sleeve. A collar 46 is clamped on the end of this rod, while a collar 47 is clamped to the end of the sleeve by a screw 48. This last-named collar has an opening therethrough through which the rod 45 extends, and this rod turns freely in the opening. From the above, it will be apparent 55 that, when the rod 45 is moved endwise, it will cause the looper supporting shaft to move endwise, but said looper supporting shaft is free to oscillate on its connection with said rod 45. The rod 45 at its outer 60 end is connected by a link 49 with an arm 65

50 carried by a sleeve 51 which is mounted to oscillate about a vertical post 52. Said sleeve 51 has a second arm 53 which is connected to an eccentric strap 54. The eccentric strap 54 co-operates with an eccentric 70 75 75 from the main shaft 8. As the main shaft rotates, this eccentric will oscillate the sleeve 51 and the sleeve through the link connection 49 and the rod 45 will move the looper supporting shaft endwise.

From the above, it will be apparent that we have provided devices for moving the loopers back and forth, into and out of the needle loops, and also for moving the loopers laterally, which devices are of few parts 80 free from springs and any irregularly shaped cams so that the machine may be driven at high speed with little vibration in the parts so that the operating mechanism is 85 strong and durable. It will be understood that the means for oscillating the loopers and the means for moving the loopers endwise are timed so that the loopers move forward into their respective needle loops with little or no lateral movement until the points 90 of the needles are far above the loopers, after which the loopers are moved laterally for their needle avoiding movements, and during this lateral or needle avoiding movement there is comparatively little backward 95 movement of the loopers and this holds the looper thread substantially taut. After the loopers have been positioned on the other sides of the needles, they are moved backward with little or no lateral movement until the points of the loopers have passed the 100 needles, after which they have returned to their first or initial position for their forward movement.

It is obvious that minor changes in the 105 details of construction and the arrangement of parts may be made without departing from the spirit of this invention as set forth in the appended claims.

Having thus described our invention, what we claim as new and desire to secure by Letters Patent, is:—

1. The combination of a work support, a main shaft located beneath the work support, a looper, a looper supporting shaft on which said looper is mounted, means for oscillating said looper supporting shaft and means for moving the looper supporting shaft endwise for giving the looper a needle avoiding movement, said last named means including a sleeve secured to the looper supporting shaft and projecting beyond the end thereof, a rod extending into said sleeve, a collar on said rod, means clamped in the end of the sleeve for holding the collar in the sleeve and permitting the sleeve to oscillate freely on the rod and means for moving the rod endwise from the main shaft.

2. The combination of a work support, a main shaft located beneath the work sup-

port, a looper, a looper supporting shaft on which said looper is mounted, means for oscillating said looper supporting shaft and means for moving the looper supporting shaft endwise for giving the looper a needle avoiding movement, said last named means including a sleeve secured to the looper supporting shaft and projecting beyond the end thereof, a rod extending into said sleeve, a collar on said rod, means clamped in the end of the sleeve for holding the collar in the sleeve and permitting the sleeve to oscillate freely on the rod, a sleeve mounted to oscillate about a vertical axis, an eccentric on the main shaft, an eccentric strap coöperating therewith, said eccentric strap being connected to the sleeve for oscillating the same and a link for connecting the rod to the sleeve whereby the oscillations of the sleeve move the rod endwise.

3. The combination of a work support, a plurality of needles, a looper for each needle, a looper holder for each looper, a looper carrier on which all of said looper holders

are adjustably mounted, a looper supporting shaft for said carrier and means for oscillating said shaft and moving the same endwise whereby the looper is moved into and out of the needle loop and is moved laterally for its needle avoiding movement.

4. The combination of a work support, a plurality of needles, a looper coöperating with each needle, a looper holder for each looper, a looper carrier having a slotted bar, means for clamping said holders to said slotted bar whereby the same may be adjusted lengthwise of the bar, a looper supporting shaft for said looper carrier and means for oscillating said looper supporting shaft and for moving the same endwise.

In testimony whereof, we affix our signatures, in the presence of two witnesses.

JAMES R. MOFFATT.
RALPH S. KELSO.
